COMBUSTION CONTROL

Homer E. Malone, Milwaukee, and Clifford Hotchkiss, St. Francis, Wis., assignors to Perfex Corporation, Milwaukee, Wis., a corporation of Wisconsin

Application June 23, 1941, Serial No. 399,378

16 Claims. (Cl. 110—72)

1

This invention relates in general to combustion control and more particularly to the control of air feeding with fuel feeding in stoker fired furnace installations.

In stoker fired furnace installations of the type in which the stoker is stopped and started in accordance with the demand for heat, difficulty has been encountered due to fly ash. During the "off" period of the stoker, the fire burns down to a point below the tuyères. When the stoker is started up the forced draft below the loose ash from the fuel bed and up the stack, depositing some of it on the furnace heat absorbing surfaces. In order to overcome this difficulty it has been proposed to delay the delivery of air for a period of time after the stoker is placed into operation. When this is done the feeding of fuel to the fuel bed increases the thickness thereof and also causes the bed to vibrate, which shakes the loose ash down into the bed where it fuses. Then when the air feed is gradually started the ash is retained in the fuel bed and thus fly ash is avoided.

The primary object of this invention is the provision of improved control apparatus for providing a delay between the feeding of fuel and the feeding of air in a fuel burner.

It has been proposed to control an air damper of a stoker by means of a thermostatic element and heater, the heater being connected in parallel with the stoker motor and the thermostatic element serving to position the damper. With this arrangement the damper is opened a period of time after the stoker starts. One difficulty with this type of arrangement is that a short timing period could not be obtained without having the heater and thermostatic element run at a very hot temperature during normal operation of the stoker. It is a further object of the invention to provide a thermal air control device in which the heating means is energized at a relatively high rate at the beginning of the timing period and in which the energization of the heating means is reduced thereafter.

Another object of the invention is the provision of a thermal air control device having a motion transmitting means between a thermal element and an air control element, this motion transmitting means including an arrangement providing for lost motion to permit continued movement of one of the elements after stopping of the other element.

Another object is the provision of thermal air control apparatus in which an air damper is moved upon initial movement of a thermal ele-

2

ment and irrespective of the actual temperature of the thermal element.

Another object is the provision of an air control device having an adjustable stop for limiting movement of the damper in one direction and in which the operating device for the damper is free to continue movement after movement of the damper is arrested by the adjustable stop.

Other objects of this invention will appear from the following description and the appended claims.

For a full disclosure of the invention reference is made to the following detailed description and to the accompanying drawing, in which

Fig. 1 shows diagrammatically a control system for a stoker such as used for domestic purposes;

Fig. 2 is an elevation of the air damper operating mechanism of Fig. 1;

Fig. 3 is a cross section of the air duct showing the air damper and taken on line 3—3 of Fig. 2;

Fig. 4 is a bottom view of the operating unit taken on line 4—4 of Fig. 2.

Referring in particular to Figs. 1 and 2, reference character 1 indicates generally a stoker of the type generally employed in house heating, this stoker being of usual form having a retort 2, a hopper 3, a coal conveyor 4 and an air conduit 5. The stoker also includes a motor 6 which drives a fan 7 for supplying air, and which also drives the coal conveyor means, not shown. The motor 6 is controlled by means of a relay generally indicated as 8; this relay including a coil 9 which operates a switch arm 10 through a suitable armature means, not shown. When coil 9 is energized the switch arm 10 is caused to engage a contact 11. When this coil is deenergized the switch arm 10 becomes disengaged from this contact as shown. The relay 9 is energized by means of a transformer 12 having a secondary coil 13 and a primary coil 14, the latter being connected across line wires 16 and 17. The relay coil 9 is controlled primarily by means of a room thermostat 18 which is connected in series with the secondary 13 and coil 9. When this thermostat calls for heat it energizes coil 9 which causes the switch arm 10 to engage contact 11. This completes an energizing circuit for the motor 6 as follows: from line wire 16, wire 19, switch arm 10, wire 20, motor 6 and wire 21 to line wire 17. When the room thermostat becomes satisfied the relay is deenergized, which stops the stoker motor. The relay coil 9 may also be controlled by a suitable hold

55

fire device which is indicated as a timer 22, this timer having a synchronous motor 23 which is connected across line wires 16 and 17, driving a cam 24 which operates a switching mechanism 25 connected in parallel with thermostat 18. This timer serves to operate the stoker independently of the thermostat for short periods which are sufficient to maintain the fire alive during mild weather when the thermostat remains satisfied for long periods of time.

The stoker 1 also includes an air control device generally indicated as 28, the details of which are shown in Fig. 2. Referring to this figure, an air damper 29 is located within the air duct 5 and is fixed to a pivotally mounted shaft 30 which extends through the side of the duct, this shaft being secured to a disc 31 which forms a part of a motion transmitting means. The shaft 30 also includes a ratchet wheel 32 which is free to rotate with respect to the shaft. The disc 31 carries a pair of pawls 33 and 34, which pawls have faces 35 and 36 which are adapted to engage the teeth on the ratchet wheel 32. The pawls 33 and 34 are carried by pivot pins 37 and 38 which are secured to the disc 31. The pawls 33 and 34 also include extension portions 39 and 40 between which extends a compression spring 41. This spring urges both pawls toward engagement with the teeth on ratchet wheel 32. The pawls 33 and 34 extend beyond the edge of disc 31, the pawl 33 being adapted to engage a fixed stop member 42 which may be secured to the air duct 5, and the pawl 34 being adapted to engage an adjustable stop member 43. This stop member 43 may be carried by a plate 44, this plate being pivoted to the shaft 30 and having an arcuate slot 45 therein for receiving a set screw 46 which screws into the air duct 5. This arrangement permits adjustment of the stop member 43 to any desired position, the screw 46 then being tightened for locking it in such position. If desired the duct 5 and the plate 44 may carry suitable indicia 47 for indicating the position to which the damper is adjusted to open.

The ratchet wheel 32 is rotated by means of a thermal damper operator generally indicated as 50. This operator may consist of a base 51 which is mounted on the duct 5 and which is provided with out-turned portions 52 and 53 which form the side walls of a housing. A suitable cover for the housing may be screwed thereto by means of screws 54. Located within the housing is a thermostatic actuator or operating unit generally indicated as 56. This unit may include a first bimetal element 57 which is attached to the wall portion 53 by means of a bracket 58. The other end of element 57 is attached to a spacer 59 which in turn is attached to a second bimetal element 60. The elements 57 and 60 are turned oppositely so that the position of the free end of element 60 is determined by the cumulative effect of both elements. The free end of element 60 is attached to a cantilever portion 61 which is attached by a link 62 to a pin 63 secured to the ratchet wheel 32. The operating unit 56 also includes a center tapped electric heater 64. When this electric heating means is energized the elements 57 and 60 warp for causing upward movement of the cantilever portion 61, which through the link 62 causes clockwise rotation of the ratchet wheel 32. When the electric heater 64 is deenergized the bimetal elements cool and return to the position shown, thus causing counterclockwise rotation of the ratchet wheel 32. Preferably, the electric heater 64 is secured at its mid-portion

to element 57 by a rivet 65. This heater may also be backed by a copper strip 65 which is also secured to the element 57 by a rivet 65', the ends of this strip extending through holes in element 57 and being bent inwardly as shown. This serves to conduct heat from the heater to element 57 even when this element is flexed, for permitting quick heating of this element.

The base 51 may also carry a terminal board 66 which is secured to the side walls 52 and 53 by brackets 67. This terminal board 66 carries terminals 68 and 69. It also may carry a portion of a switching mechanism for the heater 64. This switching mechanism may consist of a pair of spring contact blades 70 and 71 which are carried by a screw 72, these blades being spaced apart by an insulating spacer 73, and being spaced from the panel 66 by a spacer 74. A rigid blade 75 is preferably located adjacent the spring blade 70 for limiting upward movement of this blade. The blade 71 is adapted to be pressed into engagement with the blade 70 by means of an operating member 76 which is secured to the cantilever portion 61. The position of the free end of element 76 may be adjusted by means of an adjusting screw 77. When the thermostatic element formed of bimetal elements 57 and 60 is cold, the parts assume the position shown in which the contact blade 71 is pressed into engagement with contact blade 70, this blade at this time being pressed away from its stop 75. As the thermostatic element heats up, the cantilever portion 61 rises and the switch operating member 76 rises correspondingly. During this movement the contact blades 70 and 71 move upwardly together and remain engaged. However, upon continued movement the blade 70 engages its stop 75 so that upon slightly further movement of the bimetal element the contact blade 71 disengages the contact blade 70. It will be noted that the terminal 68 is connected by a wire 80 to wire 20 (in Fig. 1) and the terminal 69 is connected by wire 81 to the ground wire 21. This ground terminal 69 is attached by a lead 82 to the center of heater 64. The terminal 68 is attached directly to one portion of the heater 64 by a lead 83 and is also attached by a lead 84 to the spring blade 71, the cooperating spring blade 70 being attached by a lead 85 to the other end of heater 64.

Operation

With the parts in the positions shown, the room thermostat 18 is satisfied and the relay 8 is deenergized, thus deenergizing the stoker motor 6 and also the electric heater 64 of the damper operator. The thermostatic element of the damper operator is also cool which causes the cantilever portion 61 to assume the position shown in which the damper 29 is in closed position. At this time the contact blade 71 is pressed into engagement with contact blade 70 and thus both portions of the heater 64 are connected in parallel with the stoker motor 6. When the room thermostat 18 calls for heat, the relay 8 is energized which in turn energizes the stoker motor 6 and both portions of the heater 64. The stoker therefore feeds coal to the retort 2, increasing the thickness of the fuel bed and at the same time agitating the coal in the bed so that any free ash may be shaken down into the bed. With both sections of the heater 64 energized, the thermostatic actuator becomes heated relatively rapidly, which causes upward movement of the cantilever portion 61 and clockwise rotation of the ratchet wheel 32. Due to a tooth

on this ratchet wheel engaging the surface 36 of pawl 34 this clockwise movement of the ratchet wheel 32 causes simultaneous clockwise movement of the disc 31 and damper 29, thus slowly moving the damper 29 toward open position. When the damper is rotated to approximately the predetermined maximum open position as determined by the adjustment of plate 44 the pawl 34 engages stop 43. Upon slightly further rotation of the disc 31 the pawl 34 is caused to ride clear of the ratchet wheel 32. Consequently the ratchet wheel 32 is now free to rotate, which permits continued movement of the bimetal element under the action of its heating means. This arrangement prevents any straining of the bimetal element. When the bimetal element warps to a point in which the contact blade 71 is permitted to disengage blade 70, the right hand portion of the heater 64 is deenergized. This reduces the running temperature of the thermostatic element and also prolongs the life of heater 64.

When the room thermostat 18 becomes satisfied the relay 8 is deenergized, which stops the stoker motor 6 and also deenergizes the heater 64. The thermostatic element and heater, due to the thermal inertia thereof, remain hot for a period of time after the stoker stops, and consequently the damper 29 remains open for a period of time. This permits a supply of air to the fire by natural draft, which serves to supply air to the fuel bed for burning off the volatile constituents of the green coal supplied to the fuel bed just before the stoker stopped. This delay in closing of the damper 29 following stopping of the stoker thus serves to reduce smoking. At this time the end of pawl 33 is disengaged from the stop 42 and consequently the surface 35 of this pawl is in engagement with a tooth on the ratchet wheel. When the thermostatic element begins cooling, the cantilever portion 61 moves downwardly causing counterclockwise rotation of the ratchet wheel 32, and due to the engagement of pawl 33 therewith, the disc 31 rotates correspondingly for rotating the damper toward closed position. When the damper 29 reaches the predetermined closed position the pawl 33 engages the stop 42, and thus further rotation of the ratchet wheel 32 causes the pawl 33 to ride clear of the ratchet wheel as shown for permitting free movement of this wheel. As a result the thermostatic element is free to return to its normal cold position as shown, without any stress being placed on this element or other parts of the motion transmitting means. During the cooling movement of the thermostatic element the switch operating member 76 presses contact blade 71 into engagement with blade 70, further downward movement of member 76 resulting in flexing of both blades as shown.

From the above description it will be apparent that the lost motion transmitting means serves to permit free movement of the thermostatic element after the damper is shifted to running position, this serving to prevent straining of the element. This same arrangement also provides for immediate movement of the damper one way or the other, with initial movement of the thermostatic element in one direction or the other, irrespective of the actual temperature of the thermostatic element. This arrangement provides for actuating the damper by change in temperature of the thermostatic element. This automatically compensates for the effect of ambient temperature and also provides better con-

trol of the opening and closing movements of the damper. It will also be apparent that the arrangement above described provides for utilization of a maximum amount of heat upon initial movement of the damper, the heater then being partially deenergized until movement of the damper in the opposite direction is desired. This arrangement conserves on current consumption and reduces the running temperature of the thermostatic element, thereby increasing the life of this element and of the heater. In addition, this arrangement increases the flexibility in timing of the device.

As many variations may be made from the embodiments illustrated without departing from the scope of the invention, it is desired to be limited only by the scope of the appended claims.

What is claimed is:

1. In a control system for a stoker having fuel feeding means and air feeding means, the combination of, a controller for starting and stopping the fuel feeding means, a damper for controlling the air feeding means, a thermostatic element having electric heating means therefor, a damper operating element, motion transmitting means between said thermostatic element and said damper operating element, said motion transmitting means comprising a first member attached to the damper operating element and a second member cooperating with the first member and attached to the thermostatic element, means for causing said second member to move the first member upon initial movement of the second member in either direction while permitting continued movement of the second member in either direction after movement of the first member in the corresponding direction is stopped, and means for energizing or deenergizing said electric heating means to cause movement of the damper to air retarding position when the fuel feeding means is out of operation and for causing movement of the damper to air feeding position when the fuel feeding means is in operation.
2. In a control system for a stoker having fuel feeding means and air feeding means, the combination of, a controller for starting and stopping the fuel feeding means, a damper for controlling the air feeding means, a thermostatic element having electric heating means therefor, a damper operating element, motion transmitting means between said thermostatic element and said damper operating element, said motion transmitting means comprising a first member attached to the damper operating element and a second member cooperating with the first member and attached to the thermostatic element, means for limiting movement of the damper in closing direction, adjustable limiting means for limiting movement of the damper in opening direction, means associated with said first and second members and arranged to permit the second member to continue movement under the influence of said thermostatic element after movement of the first member is limited by one of said limiting means, while causing immediate movement of the first member with the second member upon initial movement of the second member in the opposite direction, and means for energizing or deenergizing said electric heating means to cause movement of the damper to air retarding position when the fuel feeding means is out of operation and for causing movement of the damper to air feeding position when the fuel feeding means is in operation.

3. In a control system for a stoker having fuel feeding means and air feeding means, the combination of, a controller for starting and stopping the fuel feeding means, a damper for controlling the air feeding means, stop means for limiting movement of the damper in closing direction, a thermostatic element, means for causing said thermostatic element to rise in temperature when the fuel feeding means is placed into operation and to fall in temperature when the fuel feeding means is placed out of operation, and self-adjusting motion transmitting means between the thermostatic element and damper, said motion transmitting means being constructed and arranged to cause movement of the damper away from said stop means toward air feeding position upon initial rise in temperature of the thermostatic element and irrespective of its actual temperature.

4. In a control system for a stoker having fuel feeding means and air feeding means, the combination of, a controller for starting and stopping the fuel feeding means, a damper for controlling the air feeding means, stop means for limiting the movement of the damper in opening direction, a thermostatic element, means for causing said thermostatic element to rise in temperature when the fuel feeding means is placed into operation and to fall in temperature when the fuel feeding means is placed out of operation, and self-adjusting motion transmitting means between the thermostatic element and damper, said motion transmitting means being constructed and arranged to cause movement of the damper away from said stop means toward air retarding position upon initial fall in temperature of the thermostatic element and irrespective of its actual temperature.

5. In a control system for a stoker having fuel feeding means and air feeding means, the combination of, a controller for starting and stopping the fuel feeding means, a damper for controlling the air feeding means, stop means providing a limited range of movement for the damper, a thermostatic element arranged to change in temperature upon starting and stopping of the stoker, and self-adjusting mechanical motion transmitting means for transmitting motive force from the thermostatic element to the damper, said motion transmitting means including means for causing movement of the damper from said stop means upon initial reversal in temperature of the thermostatic element in one direction and irrespective of the actual temperature of said thermostatic element.

6. In a control system for a stoker having fuel feeding means and air feeding means, the combination of, a controller for starting and stopping the fuel feeding means, a damper for controlling the air feeding means, stop means for limiting movement of the damper in both directions, a thermostatic element arranged to change in temperature upon starting and stopping of the stoker, and means including self-adjusting motion transmitting means between the thermostatic element and damper for causing movement of said damper from either limit of its range of movement upon an initial reversal in temperature of said thermostatic element and irrespective of the actual temperature thereof.

7. In a control system for a stoker having fuel feeding means and air feeding means, the combination of, a controller for starting and stopping the fuel feeding means, a damper for controlling the air feeding means, stop means for

limiting movement of the damper, a thermostatic element having electric heating means therefor, said electric heating means being controlled with the stoker and changing in temperature when the stoker is stopped or started, and means including self-adjusting motion transmitting means between the thermostatic element and damper for causing movement of the damper away from said stop means upon initial reversal in temperature of the thermostatic element and irrespective of the actual temperature thereof.

8. In a control system for a stoker having fuel feeding means and air feeding means, the combination of, a controller for starting and stopping the fuel feeding means, a damper for controlling the air feeding means, a thermostatic element having electric heating means therefor, said electric heating means being controlled with the stoker and changing in temperature when the stoker is stopped or started, adjustable stop means for limiting movement of the damper in air feed increasing direction, and motion transmitting means between said thermostatic element and said damper, said motion transmitting means including means for permitting continued movement of the thermostatic element after movement of the damper is stopped by said adjustable stop means, and for causing movement of the damper in the opposite direction upon initial movement of the thermostatic element in the opposite direction and irrespective of the temperature of said thermostatic element.

9. In a control system for a stoker having fuel feeding means and air feeding means, the combination of, a controller for starting and stopping the fuel feeding means, a damper for controlling the air feeding means, a thermostatic element having electric heating means therefor, said electric heating means being controlled with the stoker and changing in temperature when the stoker is stopped or started, adjustable stop means for limiting movement of the damper in air feed increasing direction, and motion transmitting means between said thermostatic element and said damper, said motion transmitting means including means for permitting continued movement of the thermostatic element after movement of the damper is stopped by said adjustable stop means.

10. In a control system for a stoker having fuel feeding means and air feeding means, the combination of, a controller for starting and stopping the fuel feeding means, a damper for controlling the air feeding means, a rotatable member attached to the damper for actuating the same, a wheel adjacent the rotatable member, a pawl pivoted to the rotatable member and engaging the wheel, a thermostatic element arranged to change in temperature when the fuel feeding means is stopped or started for rotating said wheel, and a stop engaged by the pawl when the damper is moved to a predetermined position for forcing said pawl away from said wheel for permitting continued movement of the thermostatic element while the damper remains stationary.

11. In a control system for a stoker having fuel feeding means and air feeding means, the combination of, a controller for starting and stopping the fuel feeding means, a damper for controlling the air feeding means, a rotatable member attached to the damper for actuating the same, a wheel adjacent the rotatable member, a pair of pawls pivoted to the rotatable member and engaging the wheel, said pawls being arranged to

drive the rotatable member in opposite directions, a first stop engaged by one of said pawls when the damper is moved to a first predetermined position for forcing said one pawl away from said wheel and a second stop engaged by the other of said pawls when the damper is moved to a second predetermined position for forcing said other pawl away from said wheel.

12. In combination, a rotatable device to be positioned, a rotatable drive member for driving said device, a wheel adjacent said drive member, a pair of pawls pivoted to the rotatable drive member and engaging the wheel, said pawls being arranged to drive the rotatable member in opposite directions, a thermostatic element for rotating said wheel, a first stop engaged by one of the pawls when the rotatable device reaches a first predetermined position for forcing said one pawl away from the wheel and a second stop engaged by the other of said pawls when the rotatable drive member reaches another predetermined position for forcing said other pawl away from the wheel.

13. In combination, a wheel, a thermostatic element for rotating said wheel, a rotatable member adjacent the wheel, a pair of pawls pivoted to the rotatable member and engaging the wheel, said pawls being arranged to drive the rotatable member in opposite directions, a first stop engaged by one of the pawls when the rotatable member reaches a first predetermined position for forcing one pawl away from the wheel, and a second stop engaged by the other of said pawls when the rotatable drive member reaches another predetermined position for forcing said other pawl away from the wheel.

14. In combination, a wheel, means including a thermostatic element for rotating the wheel in one direction on rise in temperature and for rotating the wheel in the opposite direction on fall in temperature, a rotatable member adjacent said

5
10
15
20
25

wheel, a pawl pivoted to the rotatable member and engaging the wheel, a stop engaged by the pawl when the rotatable member reaches a predetermined position for forcing the pawl away from the wheel thereby permitting continued movement of the thermostatic element while the rotatable member remains stationary, and means between the wheel and rotatable member for driving the rotatable member in the reverse direction upon rotation of the wheel in the reverse direction.

15. In combination, a wheel, means including a thermostatic element for rotating the wheel in one direction on rise in temperature and for rotating the wheel in the opposite direction on fall in temperature, a rotatable member adjacent said wheel, a pawl pivoted to the rotatable member and engaging the wheel, a stop engaged by the pawl when the rotatable member reaches a predetermined position for forcing the pawl away from the wheel thereby permitting continued movement of the thermostatic element while the rotatable member remains stationary, and means for driving the rotatable member in the reverse direction upon rotation of the wheel in the reverse direction.

16. In combination, a wheel, means including a thermostatic element for rotating the wheel in one direction on rise in temperature and for rotating the wheel in the opposite direction on fall in temperature, a rotatable member adjacent said wheel, a pawl pivoted to the rotatable member and engaging the wheel, and a stop engaged by the pawl when the rotatable member reaches a predetermined position for forcing the pawl away from the wheel thereby permitting continued movement of the thermostatic element while the rotatable member remains stationary.
